[57] CLAIM

The ornamental design for the combined dial and hands
for a timepiece, as shown and described.

DESCRIPTION

FIG. 1 is a top plan view of a combined dial and hands
for a timepiece showing my new design; and

FIG. 2 is a right side elevational view thereof.
The broken line showings of a watch in FIGS. 1 and 2
are for environmental purposes only and form no part
of the claimed design. The rear view, not shown, is
plain and unornamented.
